INVENTOR
G. F. FLECKENSTEIN

BY
Wilton S. Crandall,
ATTORNEY.

UNITED STATES PATENT OFFICE.

GEORGE F. FLECKENSTEIN, OF SIOUX CITY, IOWA.

DEVICE FOR INDICATING THE PRESENCE OF ARTICLES IN PIGEONHOLES.

1,306,757.

Specification of Letters Patent. Patented June 17, 1919.

Application filed October 12, 1917. Serial No. 196,102.

To all whom it may concern:

Be it known that I, GEORGE F. FLECKENSTEIN, a citizen of the United States, and a resident of Sioux City, in the county of 5 Woodbury and State of Iowa, have invented certain new and useful Improvements in Devices for Indicating the Presence of Articles in Pigeonholes, of which the following is a specification.

10 This invention relates to means for indicating the presence of articles in pigeonholes.

In hotels pigeon-hole cabinets are used in which are placed keys, personal cards, mail, 15 messages and other articles to be delivered to the guests. The pigeon-holes are usually numbered to correspond with the guest-room numbers and the cabinets are usually positioned in the rear of the clerks' counter in 20 view of the patrons when they approach the counter. Attendants and clerks are necessarily bothered considerably by patrons inquiring if there are any articles in their pigeon-holes.

25 Obviously, comparatively large articles in the pigeon-holes can be seen by the patrons, but the presence of letters, personal cards, messages and similar articles which lie flat in the pigeon-holes, cannot be ascertained 30 by the patron without inquiring of the clerk.

The present invention, therefore, has for its primary object, the production of a simple device adapted to be removably inserted in a pigeon-hole to indicate the presence of 35 articles in the pigeon-holes.

Furthermore, the invention aims to provide a simple inexpensive device adapted to be securely, yet removably inserted in a pigeon-hole and embodying means adapted 40 to support personal cards, messages, letters and similar flat articles in upright position.

With these and other objects in view, the invention consisting in the construction, combination and novel arrangement of parts 45 may be fully understood from the description, reference being had to the accompanying drawings which form a part of this application and in which like characters of reference indicate corresponding parts 50 throughout the several views, of which,—

Figure 1 is a fragmentary front elevation of a pigeon-hole cabinet having therein the device of my invention;

Fig. 2 is a horizontal section taken on the line 2—2 of Fig. 1;

Fig. 3 is a side elevation of a plurality of

the devices hung on a support as when not in use, portions of the base plates being cut away;

Fig. 4 is a central longitudinal section of 60 the device; and

Fig. 5 is a perspective view of the same.

Although I have illustrated and herein-after described the preferred embodiment of the invention I would not be understood as 65 being limited to the specific structure chosen for illustration for various alterations and modifications may be made in the details of construction and arrangement of parts without departing from the spirit and scope of 70 the invention.

Referring, now, to the illustrations, the cabinet shown consists of a plurality of pigeon-holes formed by horizontal and vertical partitions, 6 and 7, respectively. The 75 pigeon-holes are labeled with identifying characters, 8. My device consists preferably of an elongated sheet-metal base plate, 9, adapted to be removably placed on the bottom of the pigeon hole. The front end portion, 10, of the plate is bent upwardly at right angles to the base plate and the side edges of the upwardly bent portion are overturned toward each other as at 11, thus adapting the upright portion to retain a personal card, 12, or other flat article. At its 80 bend the plate is provided with a forwardly-extending ear, 13, which is punched from the horizontal portion of the plate. The said ear serves as a stop for small articles 85 which fall loosely between the overturned flanges, 11 or the upright member.

One side of the base plate is cut away from one rear corner toward the diagonally opposite corner as at 14, and thence laterally 95 as at 15, at a point a distance in the rear of the upright member whereby the plate may be moved outwardly and rearwardly as shown in dotted lines in Fig. 2 to permit large articles being inserted in the pigeon-hole at the side of the device. Adjacent its rear end the plate is provided with an elongated slit, 16, adapted to receive a pin, 17, on an upright support 18, whereby a plurality 100 of the devices when not in use may be hung 105 on the pin, base to base, with the upright members in superposed positions, all as shown in Fig. 3.

In operation the attendant places the device in the pigeon hole, as shown, to indicate that the pigeon hole contains an article 110 for the patron.

Having thus described my invention what I claim as new and desire to secure by Letters Patent of the United States, is,—

- 5 1. A device for indicating the presence of articles in pigeon-holes, including a rectangular plate adapted to rest on the bottom of a pigeon-hole, and an upright card-retaining plate on the front end thereof, said first plate being cut away from one rear corner 10 diagonally toward the front end and the opposite side edge, and thence laterally to the adjacent side edge, whereby the front end of said first plate may be moved laterally in the pigeon-hole to admit relatively large 15 articles thereinto.
2. A device for indicating the presence of articles in a pigeon hole comprising a base-plate adapted to be removably inserted in the pigeon-hole, and an upright member on 20 the front end of the plate, the plate having

an elongated slot adapted to receive a supporting pin, whereby a plurality of the plates may be hung on the pin.

3. A device for indicating the presence of articles in a pigeon hole, comprising an elongated base plate adapted to be removably inserted in the pigeon-hole, and having its front end portion bent upwardly, the side edge portions of said end portion being overturned to retain cards and the like and the plate being cut away from one rear corner 25 diagonally toward the front end and thence laterally to the side edge, whereby the front end of the plate may be moved laterally in the pigeon-hole to admit comparatively large 30 articles in the pigeon hole.

In testimony whereof, I have hereunto set my hand this 9th day of October, 1917.

GEORGE F. FLECKENSTEIN.
